UNITED STATES PATENT OFFICE.

OTTO HARPOLD, OF ROSEDALE, INDIANA.

ACETYLENE-GAS LAMP.

1,373,328.

Specification of Letters Patent. Patented Mar. 29, 1921.

Application filed July 21, 1916. Serial No. 110,562.

To all whom it may concern:

Be it known that I, OTTO HARPOLD, a citizen of the United States, residing at Rosedale, in the county of Parks and State 5 of Indiana, have invented new and useful Improvements in Acetylene-Gas Lamps, of which the following is a specification.

My present invention relates to improvements in acetylene gas lamps and more especially to those of the type adapted particularly for use by miners. The primary objects of the invention are to provide a lamp of this character which will be capable of efficient and reliable operation and which 15 can be recharged and cleaned if necessary with facility; to provide a lamp of this character which can be manufactured inexpensively and yet be durable; to provide improved means for holding the carbid receptacle in proper relation to the water tank; to provide a lamp which can be carried with convenience and comfort upon a miner's cap; and to provide other features of advantage as will hereinafter appear.

To these and other ends, the invention consists in certain improvements, and combinations and arrangements of parts, all as will be hereinafter more fully described, the novel features being pointed out particularly in the claims at the end of the specification.

In the accompanying drawings:—

Figure 1 is a perspective view of an acetylene gas lamp constructed in accordance with the present invention, the lamp shown in this embodiment of the invention being of the type adapted to be carried on a miner's cap.

Fig. 2 represents a vertical section 40 through the lamp taken on a diameter thereof which intersects the burner, the water supply to the carbid being shown cut off in this figure.

Fig. 3 represents a vertical section 45 through the lamp on the line 3—3, Fig. 2, and

Fig. 4 is a detail perspective view of the water supply nozzle.

Similar parts are designated by the same 50 reference characters in the several views.

Certain features of the present invention are applicable generally to acetylene gas generators or lamps while other features are 55 peculiarly advantageous in connection with miners' lamps. The preferred embodiment of the invention is shown in the accompany-

ing drawings and will be hereinafter described in detail, the invention in this instance being embodied in a lamp of the type adapted to be carried upon miners' caps. 60 It is to be understood, however, that the invention is not restricted to the precise construction shown, as equivalent constructions are contemplated and will be included within the scope of the claims.

In the present instance the lamp comprises a water tank 1, a carbid receptacle 2, a burner 3, and means to be hereinafter described for controlling the flow of water from the water tank to the carbid in the carbid receptacle. In applying the invention to miner's lamps, particularly of the type adapted to be carried on the front of the miner's cap, it is preferable to form the water tank 1 with a flat or substantially flat 70 rear wall 4 while the front of this tank may be round, as shown. A hook or equivalent attaching device 5 is secured to the water tank and provides means for attaching the lamp to the miner's cap. By forming the 75 rear wall 4 of the water tank flat, or substantially so, a relatively flat fit is provided in the lamp and the cap which will prevent lateral rocking or rolling of the lamp relatively to the cap. It is also preferable in 80 such cases to make the water tank of a size larger than the diameter of the carbid receptacle or to otherwise construct the water tank whereby the latter will overhang at the rear the carbid receptacle, as will appear 85 from Fig. 2. With this arrangement, the water tank will be in contact with the front of the miner's cap while the carbid receptacle will be spaced forwardly from the cap, and the heat generated by the formation of 90 gas from the carbid in the carbid receptacle will give no discomfort to the miner. Any suitable means may be provided for introducing water into the water tank. As 95 shown, a tapered nipple 6 is formed on the top of the tank through which water may be introduced, and a cap 7 is provided which cap normally closes the opening in the nipple. The cap is preferably hinged at one side of the nipple 6, as at 8, while a manually releasable catch 9 cooperates with its opposite side to hold it normally in closed position. In order to admit air to the water tank but to exclude dirt or foreign matter therefrom, an upwardly bowed tube 10 is 100 fitted to the top of the water tank, one or both ends of the tube opening into the water

5 tank at the under side of the top thereof, and a vent or air inlet 11 is formed in the under side of the tube 10 above the top of the water tank. This arrangement enables air to enter the water tank through the opening 11 in the under side of the tube 10, but dirt or foreign matter dropping upon the top of the lamp cannot enter the water tank, and hence clogging of the water passages of the lamp by 10 dirt or foreign matter is relieved.

15 The carbid receptacle 2 has a proper gas-tight fit upon the under side of the water tank. As shown, the upper edge of the carbid receptacle is rolled, as at 12, and is adapted to fit between a pair of flanges 13 and 14 which project downwardly from the under side of the water tank, a gasket 15 being contained between the flanges and engaged by the upper rolled edge of the carbid 20 receptacle.

25 The present invention provides means for attaching and releasing the carbid receptacle relatively to the water tank, and such means serves to maintain a proper gas-tight fit between these parts even though the lamp may be subjected to more or less shock. As shown, the lower edge of the carbid receptacle is serrated circumferentially, as at 16, and a yoke 17 is provided the upper ends 30 of which have eyes 18 and the sides of which have resilient bends or coils 19 formed therein. The lower or intermediate portion of the yoke is adapted to extend across the bottom of the carbid receptacle and to engage the serrated edge 16 thereof diametrically. A bail 20 is pivoted at opposite sides of the water tank, this bail having loops 21 formed therein which loops pass through the eyes 18 on the upper ends of the yoke 35 17. The bail 20 has offset portions 22 near its pivots whereby, when the bail occupies the dotted line position shown in Fig. 2, the yoke will be lowered sufficiently to enable its lower portion to be disengaged from the bottom of the carbid receptacle and swung 40 to one side thereof, thus permitting removal of the carbid receptacle, while when the bail is swung in a reverse direction, tension in an upward direction is exerted upon the yoke, drawing the lower portion thereof upwardly against the bottom of the carbid receptacle and thereby holding the upper rolled edge of this receptacle in gas-tight 45 engagement with the gasket 15. The coils 50 or bends 19 in the side arms of the yoke afford sufficient elasticity to maintain a gas-tight joint between the water tank and the carbid receptacle, even though the lamp be subjected to shock or forces tending to separate the water tank and carbid receptacle. While the bail is in position to hold the carbid receptacle in operative relation with the water tank, its middle or operating portion rests upon the top of the water tank, as 55 60 65 appears in Figs. 1 and 2.

70 The bottom of the water tank is provided with a gas passage or port 23, and a chamber 24 is provided above this port to contain a body of cotton or other filtering material 25. A gas outlet tube 26 leads from the chamber 24 forwardly through the forward wall of the water tank and is provided exteriorly of the water tank with a threaded nipple 27. The burner 3 is fitted into the nipple 27. The reflector 28 is preferably 75 secured in position by a cap 29, which cap also serves as a protector for the burner. As shown, the nipple 27 has a square or angular portion 30 adjacent to the forward wall of the water tank and the reflector has 80 a square or angular opening 31 to fit over the correspondingly shaped portion 30. The cap 29 is screwed upon the nipple and when in position thereon it clamps the reflector between its rear edge and the front wall of 85 the water tank. The reflector may be provided with an opening 32 for the application of an igniter for the burner should such an attachment be desired. The forward end of the cap 29 has an opening 33 90 in line with the burner to avoid obstructing the flame.

95 The means provided by the present invention for supplying water from the water tank to the carbid in the carbid receptacle comprises a sleeve 34 which has a tight fit at its top in the top wall of the water tank, its lower portion has a tight fit in the bottom of the water tank, and its lower end projects for a suitable distance below the 100 water tank and to an appropriate depth into the carbid receptacle. This sleeve has an opening 35 at or near the bottom of the water tank through which water may enter the sleeve. The bottom of the sleeve is 105 closed, as at 36, and a nipple 37 projects upwardly from the bottom 36, this nipple having a port 38 therein. A tube 39 of a size smaller than the sleeve 34 is fitted within said sleeve, the upper end of this tube 110 having a threaded portion 40 which engages a correspondingly threaded portion 41 in the sleeve, and an operating head or handle 42 is fixed to the tube and is exposed for manipulation above the top of the water tank. The lower end of the tube 39 fits closely over the upstanding nipple 37, the tube being lowered to close the port 38 in this nipple when the head or handle 42 is turned in one direction while the lower end of the tube 115 will be lifted to uncover the opening 38 in the upstanding nipple when the head or handle 42 is turned in a reverse direction. These two positions of the tube 39 are shown in Figs. 2 and 3 respectively, the supply of 120 water to the carbid being cut off, in Fig. 2, while water may flow to the carbid when the tube 39 is adjusted to the position shown in Fig. 3. A water nozzle is applied to the 125 downwardly projecting end of the sleeve 34 130

and, according to the present invention, means is provided for preventing clogging of this nozzle by the residue of the carbid in the carbid receptacle. As shown, the 5 nozzle has a substantially conical lower end 43 having an outlet opening 44 therein, and it has a tubular portion which has diametrical slots 45 which split the tubular portion into two segmental sections. This tubular 10 portion of the nozzle is flared or enlarged toward its upper end and it is adapted to fit over the lower end of the sleeve 34. The nozzle is retained on the sleeve 34 by a clamping ring 46 which, when slipped upwardly on the tubular portion of the nozzle, contracts the same upon the sleeve 34. In order to prevent clogging of the water outlet 44 of the nozzle, a stem 47 which may be made of wire extends downwardly through 15 the nipple 37 and through the water outlet 44, this stem having cross-arms 48 which rest in the diametrical slots 45 in the nozzle. In recharging the lamp, should the nozzle become clogged with the residue of the consumed carbid, the water outlet 44 may be 20 readily cleaned by reciprocating the stem 47 by manipulation of one of the cross-arms 48. This may be done while the carbid receptacle is detached but without the necessity of removing the nozzle from the 25 sleeve 34.

The operation of the lamp is, briefly, as follows:—The carbid receptacle is detached from the water tank by manipulation of the 30 bail to bring it into the dotted line position shown in Fig. 2, and carbid is placed in the carbid receptacle to a depth of about half the height of this receptacle. The carbid receptacle is then replaced upon the water 35 tank and it is fastened thereto by engaging the yoke diametrically upon the serrated lower edge of the carbid receptacle and swinging the bail into the position shown by the full lines in Fig. 2. Water is then introduced into the water tank through the cap 40 7. When it is desired to use the lamp, the head or handle 42 is turned to raise the tube 39 from the position shown in Fig. 2 to the 45 position shown in Fig. 3, water then flowing from the tank through the opening 35 downwardly in the sleeve 34, through the port 38, and then through the opening 44 in the nozzle, thus reaching the carbid and generating acetylene gas in the usual way. The head 50 55 or handle 42 is adjusted to admit the proper amount of water to produce the desired amount of gas. The gas generated from the carbid passes through the filter 25 and tube 26 to the burner 3, gas being ignited at the 60 burner in any of the usual ways.

I claim as my invention:—

1. An acetylene miner's lamp comprising

a water tank, a carbid receptacle to detachably fit the same, and means for resiliently holding the carbid receptacle and water tank 65 in cooperative relation comprising a yoke having an intermediate portion to engage the carbid receptacle and arms formed with resilient coils arranged alongside of the carbid receptacle and water tank, and a bail 70 pivoted to the water tank and operatively connected to the ends of the arms of the yoke, the bail being movable to apply or to remove endwise tension on the arms of the yoke. 75

2. An acetylene lamp comprising a water tank, a carbid receptacle adapted to removably fit against the bottom of said tank, and means for resiliently holding the carbid receptacle in cooperative relation with the water tank, said means comprising a yoke having an intermediate portion to extend across the bottom of the carbid receptacle and having upwardly extending arms arranged at opposite sides of the carbid receptacle and 80 water tank formed with resilient coils, the upper ends of said arms being formed with eyes, and a bail pivotally connected to the water tank and arranged on the upper side thereof, the sides of the bail adjacent to their 85 pivots being formed with loops which pivotally engage the eyes on the upper ends of the arms of the bail, the bail when swung into one position applying and maintaining longitudinal tension on the arms of the yoke 90 and when swung into a reverse position relieving such tension to permit detachment of the carbid receptacle from the water tank. 95

3. An acetylene lamp comprising a water tank, a carbid receptacle adapted to fit 100 against the bottom of the water tank and having a serrated lower edge, a yoke having an intermediate portion adapted to engage diametrically opposite serrations in the lower edge of the carbid receptacle and having upwardly extending arms at opposite sides of the carbid receptacle and water tank, said arms being formed with resilient coils and having eyes at their upper ends, and a bail having its ends pivoted at opposite sides 105 of the water tank near the top thereof, the bail being formed near its pivot points with loops which pivotally engage the eyes of the yoke and the intermediate portion of the bail being movable into a position on the top of the water tank to apply and maintain longitudinal tension on the arms of the yoke. 110 115

In testimony whereof I have hereunto set my hand in presence of two subscribing witnesses.

OTTO HARPOLD.
